UNITED STATES PATENT OFFICE.

GEORGE GRANTFORD DUPLER, OF MONDAY, OHIO.

REINFORCEMENT FOR PICK HANDLES.

1,426,366.

Specification of Letters Patent. Patented Aug. 22, 1922.

Application filed January 6, 1922. Serial No. 527,476.

To all whom it may concern:

Be it known that I, GEORGE GRANTFORD DUPLER, a citizen of the United States, and a resident of Monday, in the county of Hocking and State of Ohio, have invented certain new and useful Improvements in Reinforcements for Pick Handles, of which the following is a specification.

This invention relates to a reenforcement 10 for pick handles or the like.

In the use of a pick in a mine or similar place for digging purposes the portion of the handle adjacent the pick is often mutilated by striking objects with the result that 15 the handle is weakened at this point and breaks.

With this in view it is the object of the present invention to provide a wrapping for the handle at the point mentioned which 20 will protect the same against being mutilated and also greatly strengthen this portion of the handle.

It is also an important object of the invention that the wrapping can in no way 25 loosen from the handle.

A further object of the invention is that the wrapping presents a relatively smooth surface.

Other objects and objects relating to de- 30 tails of construction, combination and arrangement of parts will hereinafter appear in the detailed description to follow.

The invention is illustrated by way of example in the accompanying drawings, in 35 which,

Figures 1 and 2 are perspective views illustrating the manner in which wrapping is applied to the handle.

Figure 3 is an enlarged detail perspective view further illustrating the manner in which the wrapping is applied and also showing how the ends of the wrapping wire are secured.

Figures 4 and 5 are detailed elevations of 45 the end of the handle reinforced and showing the two sides of the handles, respectively, after being wrapped.

Referring to the drawings more particu- 50 larly, H indicates generally a handle which may be of any desired finish or length and which terminates at its one end in a head

10 adapted for receiving a pick or other tool to be positioned upon the handle. In the present instance the portion of the handle to be reinforced is that adjacent the head 55 10 and generally indicated by the reference character 11. This portion 11 of the handle is relatively flat and gradually tapers toward the end of the handle opposite to its head 10.

In carrying out the present invention I provide in the handle a pair of transverse openings 12 and 13, one at each end of the portion 11. Between the openings 12 and 13 I extend a pair of spiral grooves 15 and 16, said grooves being contiguous and the groove 15 terminating with one end of the opening 12 in the handle while the similar end of the groove 16 terminates with the other end of the opening 12. The opposite 65 70 ends of the grooves 15 and 16 terminate with the ends of the opening 13 in the handle but in opposite relation with respect to the side of the handle when compared with the termination of said grooves with respect to 75 the opening 12.

For the reinforcing medium of the handle there is preferably used a flexible wire 12 which may be of copper or other material not subject to rusting and this wire is threaded through the opening 12 of the handle so that equal portions thereof indicated by the reference characters 18 and 19 may extend from opposite sides of the handle H. As 80 illustrated in Figure 3 the portions 18 and 19 of the wire are wound about the handle in the same direction and disposed in the grooves 15 and 16 respectively. As further illustrated in Figure 3 the wire 19 is brought to the opening 13 in the handle and extended therethrough. Also the wire 18 has its end portion extended through the opening 13 but in an opposite direction. The wire 18 has its end wrapped about the convolution of wire in which it terminates at 20 85 90 95 while the wire 19 is similarly connected as at 21 to the convolution of wire in which it terminates.

It should be here mentioned that before wrapping the handle with the wire W the 100 same may be treated with linseed oil or the like so that it may resist absorbing water

or dampness. Furthermore after the handle has been wrapped as shown in Figures 4 and 5 it should be painted so as to further smooth the wrapped portion thereof.

5 It should be here pointed out that the ends of the wire W may be soldered for securing the same instead of wrapping as described with equal advantages.

It should be mentioned that during the 10 use of a pick the same is subjected to water and dampness and with the result that the handle will slightly swell. Swelling of the handle will only cause the wire W to more tightly bind the same and thus in a way increase the reenforcement of the wire for 15 the handle.

While I have specifically described my invention as associated with a certain type of handle it is to be understood that I am not 20 to be so limited as indicated by the appended claims.

What I claim is:

1. In combination, a handle, a reenforcement therefor comprising a continuous 25 strand of wire extending through an opening in the handle so that equal portions of the strand of wire extend from each side of the handle and said portions wound about the handle contiguously and in the same direction 30 and the ends thereof extended through another opening adjacent where they terminate in the opposite directions and said ends each secured to the convolution of wire in which it terminates.

35 2. In combination, a handle, a reenforcement therefor comprising a continuous strand of wire extending through an opening in the handle so that equal portions of the strand of wire extend from each side 40 of the handle and said portions wound about the handle contiguously and in the same direction and the ends thereof extended through another opening adjacent where they terminate in opposite directions and 45 then secured.

3. A wrapping for reinforcing a handle comprising a continuous strand of wire secured to the handle at a point intermediate its ends to provide two equal portions and 50 then said portions wrapped about said handle in one direction and in a progressive manner and the ends thereof extended through a transverse opening in the handle adjacent to their termination and in opposite directions, and secured.

4. A wrapping for reinforcing a handle consisting in a continuous strand of wire secured at a point intermediate its ends to the handle to provide two equal portions of 60 wire, and said portions wrapped about the wire in a progressive manner and disposed in a pair of spiral and contiguous grooves and the opposite ends thereof extending through another transverse opening in the 65 handle in opposite directions and thence

each end secured to the convolution of wire in which it terminates.

5. Means for reinforcing a handle which consists in providing the handle with a pair of spiral and contiguous grooves, said 70 grooves terminating at one end in an opening extending transversely of the handle and at opposite ends of the opening and at their other end in a similar opening through the handle and in a similar manner, a wire 75 threaded through one of the openings so that equal portions thereof extend from each side of the handle and said portions of wire wrapped about the handle and disposed within the contiguous grooves and the ends 80 thereof extending through the other opening in opposite directions and each end secured to the convolutions of wire in which it terminates.

6. In combination, a handle, a reenforcement therefor comprising a flexible strand extending through an opening in the handle so that portions of the strand extend from each end of the opening in the handle, and said portions wound about the handle in a 90 contiguous manner and the ends thereof secured.

7. A reenforcement for handles comprising a continuous strand of flexible material extending through an opening in the handle 95 so that portions of the strand extend from each end of the opening in the handle, and said portions wound in contiguous spiral grooves formed about the handle and having their ends secured.

8. A handle reenforcement comprising a continuous strand of flexible material extending through an opening in the handle so that equal portions of the strand extend from each end of the opening, and said portions wound about the handle contiguously and in the same direction and having their ends secured.

9. The method of reinforcing a handle which consists in extending a continuous 110 strand of flexible material through a transverse opening in the handle so that equal portions of the strand will extend from each end of the opening then winding said strands about the handle in a contiguous manner 115 and extending the free ends through a transverse opening in the handle and securing said free ends.

10. A method of reinforcing a handle which consists in extending a strand of flexible material through a transverse opening in the handle so that portions of said strand extend from each end of the opening, wrapping said portions about the handle in the same direction and in a contiguous manner, and extending the free ends of said strand through a transverse opening in the handle where they may terminate and in opposite directions, and then securing said ends.

11. A method of reinforcing a handle which consists in extending a strand of flexible material through a transverse opening in the handle so that portions of said strand extend from each end of the opening, wrapping said portions about the handle in the same direction and in a contiguous manner, and extending the free ends of said strand through a transverse opening in the handle where they may terminate and in opposite directions, and then securing each end to the convolution of the strand in which it terminates.

GEORGE GRANTFORD DUPLER.
